FAIRLEIGH S. DICKINSON, OF RUTHERFORD, NEW JERSEY

HYPODERMIC SYRINGE

Application filed January 15, 1925. Serial No. 2,706.

The invention relates to surgical instruments of the kind generally known as hypodermic syringes and has for its object to provide means for establishing a reliable connection between the needle and the barrel. The invention, by means of which this result is obtained, involves a needle member as well as a novel structure of the barrel member. Advantages of the invention will be referred to hereinafter.

Although the invention is obviously capable of numerous other forms, I have illustrated preferred embodiments thereof in the accompanying drawings in which Fig. 1 is an elevation of the new syringe; Fig. 2 is an enlarged fragmentary sectional view approximately on line 2-2 of Fig. 1; Fig. 3 is a transverse sectional view approximately on line 3-3 of Fig. 2; Fig. 4 is a perspective view 20 of the needle shown in Fig. 1; Fig. 5 is a side view showing the needle resting upon a flat surface; Fig. 6 is a sectional view on the line 6-6 of Fig. 5 looking in the direction of the arrow; Fig. 7 is a sectional view similar 25 to Fig. 2 showing another form of the invention; Fig. 8 is a detail perspective view of the metal sleeve of the barrel member in the form shown in Fig. 7, and Fig. 9 is a fragmentary section similar to Fig. 2 illustrating 30 still another form of the invention.

Referring to the accompanying drawing by numerals, 1 indicates a syringe preferably made of glass and which is provided with a discharge nozzle 2 tapering on the outer surface so as to readily receive the hub 3 of the needle 4. Heretofore needles have been provided with hubs having bores similar to the bore 4^a of hub 3 so as to be readily slipped upon the nozzle 2 and held thereon by friction. A slip joint of this character is very desirable as it provides a good contact between the metal hub and the glass nozzle and holds the needle steady and prevents the entrance of air. When, however, the needle is used with the syringe and depends only upon friction for holding the same in place as has been the practice heretofore, it has been found that the syringe frequently becomes separated from the needle during the operation 50 thereof, particularly where a comparatively

heavy fluid is being forced through the needle. This is extremely objectionable and often dangerous as for example where the surgeon, as a result of such separation cannot be sure of the exact amount of fluid that he has forced through the needle into the patient.

Nevertheless, although such defects of existing structures have been recognized, no satisfactory remedy has thus far been found. This is in part due to the fact that the needle member may not be fastened in any permanent or troublesome detachable manner to the barrel member but must, at all times, be easily and conveniently separable at will and replaceable by a new needle.

The new invention overcomes all the difficulties and disadvantages of the prior constructions while at the same time retaining all of the advantages thereof. These results are brought about by constructing the needle member so that, while it still may be efficiently utilized in connection with the barrel members of existing syringes of the indicated type in a manner to retain all of the advantages inherent therein, it is specially adapted for use in connection with the barrel of the new syringe which includes means arranged to cooperate with means on the needle, so located with respect to each other as to prevent unintentional separation of the needle and barrel and to emphasize the desirable features which are found in the existing syringes.

In the illustrated example of the invention (Fig. 2), the syringe is provided with a sleeve-carrying element supporting the locking sleeve 5, said element being secured in place in any suitable manner upon the syringe, the method of attachment being such as to withstand separation of the parts under any ordinary conditions to which the syringe is subjected. A preferred method of accomplishing this result is to make the collar 5^a of the metal sleeve 5 slightly smaller in internal dimension than the exterior dimension of the ground glass nozzle 2 at its point of connection with said collar 5^a, then heating the latter and in its heated condition slipping it upon the relatively cool glass nozzle 2 whereupon as the metal cools a practically permanent connection will be established

between the metal sleeve 5^a and the glass nozzle 2. The process by which this is accomplished is embodied in a separate application Serial No. 2,705, filed January 15, 1925.

5 There are other methods of making a proper connection between the sleeve 5 and the syringe 1 but for the purposes of the present case any such connection is the equivalent of the preferred connection above set forth.

10 The hub 3 of the needle is of substantially the usual size and provided with the usual bore 4, and at that end which is contiguous to the needle 4 is formed with one or more flattened portions or faces 6. Near its opposite 15 end, the hub is provided with one or more faces 7 which as shown may comprise flattened portions on an upstanding flange 8 which in such case is divided into two sections by the flattened or reduced portions 7.

20 The flange 8 is comparatively thin and the two sections thereof which form projecting portions 8' on diametrically opposite sides of the hub, are substantially arc-shaped and each occupy about one-fourth of the complete flange. These projecting portions 8' constitute an example of the means on the needle whereby unintentional separation from the syringe barrel 1 is prevented by cooperation with a co-action means on the 25 locking sleeve 5; thus in the illustrated example said projecting portions 8' act as interlocking cams with the respective spiral cams 9 and 10 arranged interiorly of the locking sleeve 5. The spiral cams 9 and 10 30 may be termed threads though the action is that of spiral cams, there being two cams to accommodate the two portions 8' which interlock with the cams for holding the hub 3 in substantially the position shown in Fig. 2.

35 It will be understood that other means whereby the needle is connected with the syringe barrel in an equivalent manner so as to be easily detachable and attachable at will and so as to be fixed against unintentional separation may be substituted for the projecting portions 8' and the spiral cams 9 and 10. That is to say, any type of devices which 40 cooperate to fix the needle in place in a manner to resist forces developed by the syringe 45 when in use and exerted in a direction parallel with the surface engagement of the needle barrel with the nozzle 2 are within the purview of my claims. When the needle 4 is not in use, it may rest on a supporting surface 50 with one of the flattened faces 7 and the corresponding face 6 positioned in engagement with said supporting surface whereby the needle 4 will be held at an upward inclination with its point elevated for an appreciable distance above the support as shown 55 in Fig. 5. In combining the needle member with the barrel member, the hub is gripped and forced onto the nozzle 2 by a gentle rotation of the hub. The spiral cams 9 and 10 60 are spaced a sufficient distance apart to permit the hub to freely rotate until it begins to frictionally engage the outer surface of the nozzle 2 whereupon a final rotation of the hub with very little forward movement will cause the cam portions 8' of the needle member to engage the spiral cams 9 and 10 and act to assure a final perfection of fit and at the same time locking the hub in its perfectly seated condition against accidental removal or accidental loosening. The final rotation 70 of the hub and the resultant cam action between the projections 8' and the spiral cams 9 and 10 jams the parts together so that uncoupling by reverse rotation is resisted to an extent sufficient to prevent unseating of the cams in the ordinary operation of the syringe or unless a special effort sufficient to overcome the resistance is made. At the same time the coupling is not so resistant as to prevent uncoupling with great ease by a simple 75 manual operation applied by gripping the needle hub between two fingers of one hand and the barrel with the other hand and imparting reverse rotative movements to these elements. The sleeve 5 in addition to acting 80 as a locking sleeve or member for the hub 3, protects and tends to keep clean the outer surface of the tip or nozzle 2. Even in an exceptional case where the frictional engagement between the tip or nozzle 2 and the hub 3 fails accidentally to be established or a separation takes place from any cause, the cam portions or members 8' will nevertheless 85 co-act with the spiral cams 9 and 10 to hold the hub against disengagement so that the surgeon may without impediment complete the operation of injecting the fluid into the patient.

90 In cases where it is desired to provide means for specially treating the nozzle with cleansing or disinfecting fluids, the sleeve 5 may be apertured at one or more points as indicated at 11 in Fig. 8. Fig. 7 also illustrates a form of the invention thus far described specially applicable to such cases 95 where long or heavy needles are involved as for example in tonsil operations, veterinary surgery, etc. In such cases the nozzle 2, as shown in Fig. 1, frequently proves too fragile to endure the strains developed during use and breaks from the barrel 1. To avoid this contingency and nevertheless retain the benefits of this invention, the glass nozzle 2^a is 100 not employed as the co-acting member for the tapered hub of the needle but is made heavy 105 and strong as indicated in Fig. 7. The metal collar 5^b is then fitted upon the nozzle 2^a in the manner previously described, while the interior of the metal sleeve structure 5^c is 110 developed as an exteriorly tapered nozzle 2^b corresponding approximately in outer dimensions with the nozzle 2 of Fig. 2. The same needle which has been used for Fig. 2 115 can be used with the structure of Fig. 7 and in the same manner as described with ref- 120

125

130

erence to Fig. 2, the locking projections 8' engaging with the spiral cams 9^a and 10^a of Fig. 7 and seating the needle hub correctly and in locked position upon the metal nozzle 2^b.

5 In order to avoid an open space between the forward edge of the glass part 2^c and the face 5' of the metal sleeve 5^c it is recommended that in putting the parts together a suitable solder be used at this point; after the parts have been united any solder that has flowed into or clogged the bore of the fluid passage is easily removable by inserting a drill or other suitable instrument through the 15 forward end of the nozzle.

In the form of the invention shown in Fig. 9, the glass nozzle 2^c similar to the nozzle 2^a of Fig. 7 extends from the barrel 1 as an integral part thereof and is continued in the 20 form of a tapering nozzle 2^d for the reception of the needle hub 3 as in Fig. 2. A metal collar 5^d similar to the collar 5^b of Fig. 7 is secured upon the nozzle 2^c in the manner previously described and is continued as a 25 sleeve 5^e which surrounds the tapering nozzle 2^d as in the previous forms. The sleeve 5^e is constructed interiorly to cooperate with the needle for holding the latter in place as hereinbefore set forth. With the arrangement shown in Fig. 9, the glass nozzle comprises a base section of maximum strength and a tapering section projecting therefrom so that the danger of breakage of the glass nozzle 2^c—2^d at its point of connection with 35 the barrel 1 is reduced to a minimum. This is due to the fact that the nozzle 2^c is of relatively large diameter and heavy construction and thus capable of withstanding more or less severe strains.

40 It will be seen that the new needle can be used with equal facility but with improved effect in connection with existing glass syringes without requiring any alteration or modification of the syringe structure. At 45 the same time, the needle member functions still more perfectly when associated with a syringe provided with the described sleeve structure. There is thus provided an improved construction wherein the desirable 50 and beneficial action of the slip joint is retained while at the same time means are presented which will positively lock the needle against slipping off of the syringe when under pressure. The sleeve structure of the new 55 barrel construction is so designed, on the other hand, that it will accommodate any standard existing needle.

60 So far as the needle member is concerned, it will be seen that a plurality of finger grips 65 are presented which act in the double capacity of finger grips and means for holding the discharge end of the needle from contact with a surface on which it may rest or be mounted, while having also permanent means 70 to adapt the needle to be used with equal fa-

cility with a plain glass syringe and with a syringe provided with the novel cooperating member above described. The needle member as such and its novel features constitute the subject of a separate divisional application.

70 A further feature of the invention is that it provides a co-acting needle and lock in connection with the nozzle of a syringe whereby the hub of the needle may be forced on the 75 tapering nozzle and be made to firmly engage the same by friction and at the same time become interlocked with the locking member secured to the syringe so that accidental loosening of the needle will not cause 80 its removal from the syringe.

85 It will also be observed that the relation between the sleeve and barrel is such as to avoid having the metal project over the sides of the barrel, thus avoiding any obstruction to the 90 complete observation of the entire interior of the barrel.

Various changes in the specific form shown and described may be made within the scope of the claims without departing from the 95 spirit of my invention.

What I claim is:

1. The combination comprising a syringe, a tapering tip associated with said syringe, a needle provided with a hub adapted to frictionally engage said tip, a sleeve carrying element rigidly associated with and supported from said syringe, and a sleeve projecting from the sleeve-carrying element formed with interlocking members in radially spaced relation to the outer surface of said tip and interlocking with said hub for preventing accidental disengagement thereof.

95 100 105 110 115 120 125 130

2. The combination comprising a syringe, a tip associated with said syringe, a sleeve-carrying element rigidly associated with and supported from said syringe, a sleeve projecting from the sleeve-carrying element in the same direction as the tip, and in radially spaced relation thereto and formed with an interlocking member and a needle provided with a hub adapted to fit said tip and to removably interlock with said interlocking member of the sleeve in the final seating of the needle on the tip and in that position developing a camming action whereby said hub is fitted to said tip and simultaneously locked.

3. The combination comprising a syringe, a tapering tip associated with said syringe, a sleeve, a sleeve-carrying element rigidly associated with and supported from said syringe, a sleeve projecting from the sleeve-carrying element and spaced from the tip and formed with a plurality of spiral cams, and a needle provided with a hub telescopically fitting over said tip and having outwardly extending webs interlocking with said spiral cams to lock the needle against accidental disengagement.

4. The combination comprising a syringe, a tapering tip associated with said syringe, a needle adapted to telescope over said tip and frictionally engage the same, said needle having laterally extending members on the hub, a sleeve-carrying element rigidly associated with and supported from said syringe, and a sleeve projecting from the sleeve-carrying element and provided with a pair of spiral cams, said cams being spaced apart to present spirally arranged grooves in which said laterally extending members of the hub of the needle are adapted to move as said hub is forced onto said tip.
5. A syringe having a discharge orifice, a sleeve-carrying element rigidly associated with and supported from the syringe, a sleeve projecting from the sleeve-carrying element, a rigid tapered nozzle the duct of which constitutes an extension of the discharge orifice of the syringe while its outer tapered surface is arranged for receiving the hub of a needle, said nozzle being integral with the sleeve-carrying element and surrounded by the sleeve thereof, and means on the sleeve adapted to cooperate with said needle hub to hold the same in frictional engagement with the tapered nozzle and to lock the same in position.
6. A syringe having a discharge orifice, a sleeve-carrying element rigidly associated with and supported from the syringe, a sleeve projecting from said sleeve-carrying element, a rigid nozzle the duct of which constitutes an extension of the discharge orifice of the syringe while its outer tapered surface is shaped to receive the hub of a needle, said nozzle being integral with the sleeve-carrying element and surrounded by the sleeve thereof, a needle having a hub adapted to fit said nozzle and provided with means to cooperate with means on the sleeve and means on said sleeve cooperating with said means on the hub to hold said hub in frictional engagement with the nozzle extension and to lock said hub in position thereon.
7. In a device of the character described, a locking sleeve adapted to be connected with a syringe, comprising a tubular portion for engaging the syringe, and a portion extending therefrom provided with a plurality of internally positioned spiral cams, said sleeve being provided with peripheral apertures through which a cleansing or disinfecting fluid may be introduced to the interior of said sleeve.
8. In a hypodermic syringe, the combination of a glass barrel, an integral nozzle of relatively large diameter projecting from one end thereof, a second nozzle projecting from said first nozzle, adapted to frictionally engage the interior of the hub of a needle, and of less diameter than the first nozzle at the needle-hub-engaging portion of said second nozzle, a metal collar fitted upon said first nozzle and a sleeve projecting from said col-
- lar and permanently surrounding said second nozzle at a distance for fixing a needle thereon against removal.
9. The combination with a syringe having a nozzle, of a needle adapted to fit over said nozzle, a locking sleeve fixed to said syringe and partially enclosing said nozzle, and interlocking cam means on said needle and said sleeve for fixedly holding the needle in position, said sleeve being provided with peripheral apertures through which a cleansing fluid may be introduced.
10. The combination with a syringe having a nozzle associated therewith, a needle member adapted to telescope over said nozzle to be held in position thereon by frictional engagement, a sleeve-carrying element fixed to said syringe, a sleeve projecting from the sleeve-carrying element, threaded means on the interior of said sleeve and means on the needle member coacting with said threaded means for forcing the needle member onto the nozzle and for holding the needle member fixedly in position thereon.
11. A syringe having a tip, a sleeve secured thereto, said sleeve being provided with a tapered nozzle constituting an extension of the tip of the syringe and being adapted to frictionally engage the interior of the hub of a needle, and threaded means on the sleeve adapted to cooperate with said needle hub to hold the same in frictional engagement with said nozzle.
12. The combination with a syringe having a tip, of a locking sleeve carried by said tip and provided with a tapered nozzle, communicating with said syringe and adapted to frictionally engage the interior of the hub of a needle, said sleeve being also provided with peripheral apertures through which a cleansing or disinfecting fluid may be introduced to flush the interior of the sleeve and the exterior of said nozzle.
- In testimony whereof I have hereunto set my hand.
- FAIRLEIGH S. DICKINSON.
